CLAIM

The ornamental design for a perfume bottle or similar article, substantially as shown and described.

DESCRIPTION

FIG. 1 is a side elevational view of a perfume bottle or similar article showing my new design, the reverse side being a mirror image thereof;

FIG. 2 is an end elevational view thereof taken from the right side of FIG. 1;

FIG. 3 is an end elevational view thereof, taken from the left side of FIG. 1;

FIG. 4 is a top plan view thereof; and

FIG. 5 is a bottom plan view thereof.

FIG. 1

FIG. 2

FIG. 3

FIG. 4

FIG. 5
